UNITED STATES PATENT OFFICE.

WILLIAM N. GORDON, OF CORRY, PENNSYLVANIA.

RAIL-JOINT.

No. 831,389.

Specification of Letters Patent.

Patented Sept. 18, 1906.

Application filed December 18, 1905. Serial No. 292,197.

To all whom it may concern:

Be it known that I, WILLIAM N. GORDON, a citizen of the United States, residing at Corry, in the county of Erie, State of Pennsylvania, have invented certain new and useful Improvements in Rail-Joints; and I do hereby declare the following to be a full, clear, and exact description of the invention, such as will enable others skilled in the art to o which it appertains to make and use the same.

This invention relates to railroad-tracks, and more particularly to rail-joints, and has for its object to provide a joint by means of which alining rails may be securely held together against lateral separation and which will also be arranged to prevent sinking of the ends of the rails.

Other objects and advantages will be apparent from the following description.

In the drawings forming a portion of this specification, and in which like numerals of reference indicate similar parts in the several views, Figure 1 is a side elevation. Fig. 2 is a horizontal section just below the treads of the rails. Fig. 3 is a transverse section.

Referring now to the drawings, the present invention comprises a casting 5, including a horizontal base-plate 6, having an upwardly-extending flange 7 at one edge and extending longitudinally thereof. At the opposite side of the base-plate the casting extends upwardly, as shown at 8, and then inwardly, as shown at 9, to form a recess 10 for the reception of one base-flange of a rail, and at its inner edge the portion 9 has an upwardly-extending vertical wall 11, formed integral therewith.

A removable member is provided and consists of a web portion 13, having a longitudinally-extending depending flange 14 at one edge and an upwardly-extending wall 15 at its other edge. This member is disposed upon the base-plate 6 inwardly of the flange 7 and with its web portion 13 extending upwardly and inwardly to form a recess 16 be-

tween it and the base-plate, the flange 14 resting against the base-plate and against the flange 7.

A plurality of alining pairs of openings 17 are formed through the base-plate, the flange 14, and the web 13 and receive confining-bolts 18.

The recesses 10 and 16, as will be seen, receive the base-flanges of rails, and the walls 55 11 and 15, which are in reality fish-plates, rest against the sides of the rail-webs. Inwardly-extending ribs 20 are formed upon these walls and bite into the webs of the rails. Confining-bolts 21 are engaged in these walls 60 and in the rails.

Upon the under face of the base-plate 6 of the casting there is a longitudinally-extending arcuate rib 22, directed downwardly, and this rib acts to prevent sagging of the casting 65 at its center.

What is claimed is—

In a rail-joint, the combination with a casting including a base-plate, having one side portion extended upwardly and inwardly 70 thereover to form a recess between it and the base-plate, said inwardly-extending portion having an upwardly-extending longitudinal wall at its inner edge, a removable member including a web portion having an upwardly-extending wall at one edge disposed in parallel relation to the first-named wall, and having a depending flange at its opposite edge resting against the inner face of the flange of the base-plate and against the base-plate, 75 said flange of the removable member and the base-plate having alining openings therein, and bolts engaged in the openings, the parallel walls of the casting and movable member, having inwardly-directed ribs and having 80 alining openings therein.

In testimony whereof I affix my signature in presence of two witnesses.

WILLIAM N. GORDON.
